(57) **CLAIM**

We claim the design for an adjustable vehicle cargo restraint device, as shown and described.

DESCRIPTION

FIG. 1 is a perspective view of the adjustable vehicle cargo restraint device, in place in the forward section of the open bed of a pick-up truck;

FIG. 2 is a side elevational view of the adjustable vehicle cargo restraint device;

FIG. 3 is a rear view of the adjustable vehicle cargo restraint device;

FIG. 4 is a bottom view of the adjustable vehicle cargo restraint device;

FIG. 5 is a top view of the adjustable vehicle cargo restraint device; and,

FIG. 6 is a front view of the adjustable vehicle cargo restraint device.

The broken line showing of a pick-up truck on FIG. 1 is for illustrative purposes only and forms no part of the claimed design.

The random criss-cross shading is understood to represent fabric material and is understood to be repeated uniformly throughout the area on which it is applied.
